FRUIT JUICER

Henry J. Talge, Kansas City, Mo., assignor to
John C. Hockery, Kansas City, Mo., trustee

Filed Oct. 18, 1961, Ser. No. 67,146

Term of patent 14 years

(Cl. D89—1)

Fig. 1.

Fig. 2.

Fig. 3.

Fig. 4.

FIG. 1 is a front elevational view of a fruit juicer embodying my design;

FIG. 2 is a side elevational view of same taken from the right-hand side of FIG. 1;

FIG. 3 is a rear elevational view of same; and

FIG. 4 is a top plan view of same.

I claim:

The ornamental design for a fruit juicer, as shown.
